DESK LAMP

Shoji Ishikawa, Nara, Japan, assignor to Matsushita
Electric Industrial Co., Ltd., Osaka, Japan, a corporation of Japan

Filed Mar. 18, 1969, Ser. No. 16,307

Term of patent 14 years

Int. Cl. D26—02

U.S. Cl. D48—20

FIG. 1 is a top plan view of a desk lamp showing my new design;

FIG. 2 is a top and front perspective view thereof,

FIG. 3 is a left side view thereof, and

FIG. 4 is a top and rear perspective view thereof with the support arm in the lowered position.

I claim:

The ornamental design for a desk lamp, as shown and described.
